UNITED STATES PATENT OFFICE.

JAMES S. KENYON, OF PROVIDENCE, RHODE ISLAND.

HEEL-NAIL.

1,257,876.

Specification of Letters Patent. Patented Feb. 26, 1918.

Application filed December 17, 1915. Serial No. 67,364.

To all whom it may concern:

Be it known that I, JAMES S. KENYON, a citizen of the United States, residing at Providence, in the county of Providence, State of Rhode Island, have invented certain new and useful Improvements in Heel-Nails, of which the following is a specification.

My invention is an improved nail for use in attaching heels to boots or shoes. The object of my improvement is to provide a nail having a relatively long shank or body portion with a point at one end and a collar at the opposite end, above which is an extension, of substantially the same diameter as the body of the nail, formed with annular grooves or corrugations to adapt it to serve as a holding-means for the top lift of the heel.

In attaching heels to boots or shoes the main portions of the heels consisting of a certain number of lifts are first nailed onto the sole and then a top lift is applied to provide a finish for the heel. In some cases the top lift is merely glued or cemented on to the other lifts to cover the heads of the nails with which the main portion of the heel is fastened, while in other instances it has already been proposed to secure the top lift by means of extensions on the nail which fasten the main lifts in place. That is to say, it has heretofore been proposed to employ a nail having a collar at one end which sets against the last lift of the main portion of the heel and which also has an extension above the collar adapted to be driven into the top lift when the latter is "spanked" into the other lifts in the usual manner. With the forms of nails as heretofore used for this purpose, however, it has been found that the top lift of the heel cannot be securely fastened in place without the use of additional means such as cement and furthermore with all such nails as previously designed the cost of manufacture has been so great as to allow for their general use being denied. The main purpose of the present invention is therefore to provide a nail having an auxiliary holding-means or extension for securing in place the top lift of the heel which is more efficient for the purpose intended, is more efficient for the purpose intended.

and which can be manufactured at a relatively small cost through the employment of the usual processes.

The manner and means for carrying out these improvements are fully described in the following specification, illustrated by the accompanying drawings, in which like reference characters designate like parts. In the drawings:—

Figure 1 shows a portion of a shoe and its heel in section and illustrates a nail embodying my improvements as applied thereto;

Fig. 2 is an enlarged view showing the wire blank from which the nail is constructed;

Fig. 3 illustrates the blank with the point and collar formed thereon;

Fig. 4 shows the nail completed by the final rolling process; and

Fig. 5 is an end view of the completed nail.

Referring first to Fig. 3, this shows an enlarged section of round wire which constitutes the blank B from which the nail is formed. The blank B is operated upon in the usual manner to form it with a driving point P at one end and adjacent its opposite end the wire is rolled in suitable dies to change it up in an annular projecting collar C. Above the collar C is the unstaggered projection or extension E of substantially the same diameter as the main body portion or shank B and of the length, preferably slightly less, than the thickness of the top lift of the heel. To complete the nail the extension E is rolled in suitable dies to score its periphery with a series of angular grooves, thereby forming a series of annular enlargements or ridges. That is to say, the extension E is peripherally fluted or corrugated so as to be provided with a series of spherical beads which are adapted to indent the material of the top lift of the heel to hold the latter securely in place. The scoring or fluting of the extension E may be performed during the operation of flanging up the collar C from the body of the nail, or it may be performed separately as a finishing operation. In either case, however, it is ac-

complished by a simple rolling action in grooved dies by a process which does not add materially to the cost of manufacture of the nail. That is to say, it costs practically no more to roll the extension E with grooves than to form the collar C, and as a matter of fact both operations whether performed singly or together may be accomplished at very slight expense. It will therefore be seen that my improved nail may be manufactured in accordance with the usual practice as employed in this art, so that its manufacture is rendered particularly economical, while its form of construction provides the advantages in use as next explained.

The method of applying my improved nail to use is illustrated in Fig. 1. The heel H here shown consists of a plurality of overlying lifts h, h', etc., and a top lift L which are united to the sole S by means of a series of nails N. The main lifts h, h' are fastened to the sole by driving the nails N through them and clenching its point P through the sole S and a part of the upper U. The collar C on the nail N will thus abut the face of the last lift h' of the heel, to serve as a holding-means therefor in the usual manner, and projecting outwardly beyond the main part 30 of the heel is the extension E of the nail arranged to receive the top lift L. The top lift L is applied by "spanking" it onto the heel in the well known manner as usually employed to cause the nail ends or extensions E to be driven into the leather. The rounded end of the extension E adapts it for easy penetration into the top lift L and the corrugations or annular grooves e allow the leather or other material to expand therearound to 40 take a grip on the nail. That is to say, as the lift L is "spanked" into place the extensions E will penetrate its material while the fibers thereof expand into the grooves or corrugations e to frictionally grip the lift thereto to effect a secure fastening. It will be seen that the extensions E do not project beyond the outer face of the lift L but are concealed from view so that a neat and finished appearance is given to the heel. In 50 this manner the top lift L can be united to the heel without any other fastening-means such as cement or glue and with the nails N entirely concealed from view.

It has been demonstrated that the novel form of extension E on the nail N as here shown provides for a most secure fastening-means for the top lift and is much superior in this respect to similarly formed nails heretofore employed for like purposes. As 60 before stated I am aware that it is not new in the art to provide a nail with an end collar having an extension projecting upwardly therefrom for fastening the top lift to the heel. Heretofore, however, such nails have

been open to certain objections; first, that they were inefficient for the purpose intended, and second, that they were too expensive to manufacture to adapt them for general use.

In one form of such a nail as previously used the extension above its collar is provided with concaved side faces which taper outwardly to a relatively broad driving end. This end being considerably larger than the body of the nail it has been found difficult to 7 drive the top lift onto it without breaking the fibers of the leather and furthermore the lift is not securely fastened after it is once in place. That is to say, the leather does not grip the sides of the extension on the nail as 8 in my improved construction and the nail is therefore not as efficient for holding the lift in place. Another objection to this form of nail as just described is that its extension cannot be formed by a rolling process but must 8 be constructed by more complicated operations. This renders the nail more expensive to manufacture so that it is not adapted for general use.

Another form of nail previously used for 9 the purpose described is designed with a wedge-shaped end formed with a shoulder and longitudinal ribs on its extension. This form of nail has also been found unsatisfactory in use as the driving end of the extension breaks the fibers of the leather so that the top lift does not grip itself securely thereto. This style of nail must also be constructed by special forming operations on its extensions instead of by simply rolling it so 10 that it is much more expensive to manufacture than the improved form of nail herein shown and described.

As before indicated I do not herein claim broadly a heel nail formed with an annular collar at one end and having an extension projecting upwardly therefrom. The particular features of my invention which constitute novelty reside in the peculiar formation of the extension on the nail whereby it 11 may be more easily penetrated into the top lift without breaking the fibers thereof; the annular grooving of the extension to provide for the gripping of the top lift thereto; and the provision for forming the nail by a rolling process whereby it may be manufactured at a relatively small cost to adapt it for general use.

What I claim is:—

An improved heel-nail having an extended body portion constructed from round wire, a driving point at its end, an annular collar flanged out from the body at its opposite end, and an extension projecting upwardly from said collar, said extension being of substantially the same diameter as the body of the nail and scored on its periphery with a plurality of annular grooves dividing it into a

8

series of spherical beads, the end of the extension being rounded off to provide for its easy penetration into the top lift of the heel and having its sides presenting a smooth surface without sharp edges liable to break or cut the fibers of the material through which it is driven.

In testimony whereof I affix my signature in presence of two witnesses.

JAMES S. KENYON.
